UNITED STATES PATENT OFFICE.

CLARENCE R. BROCK AND WILLIAM C. BARTH, OF BROUGHTON, KANSAS.

FAN.

SPECIFICATION forming part of Letters Patent No. 715,011, dated December 2, 1902.

Application filed January 28, 1902. Serial No. 91,573. (No model.)

To all whom it may concern:

Be it known that we, CLARENCE R. BROCK and WILLIAM C. BARTH, citizens of the United States, residing at Broughton, in the county of Clay and State of Kansas, have invented certain new and useful Improvements in Fans; and we do hereby declare the following to be a full, clear, and exact description of the invention, such as will enable others skilled in the art to which it appertains to make and use the same, reference being had to the accompanying drawings, and to the figures of reference marked thereon, which form a part of this specification.

15 This invention relates to fans, and particularly to rotating fans driven by a spring-motor.

The object of the invention is to provide an improved device for governing the speed of 20 the fan and for stopping the same.

A further object is to construct an improved bearing for the fan-shaft.

With these and other objects in view an embodiment of the invention is hereinafter 25 described and is illustrated in the accompanying drawings, in which—

Figure 1 is a side elevation of the device, part of the casing being removed to show the interior thereof. Fig. 2 is a sectional view 30 on a larger scale.

Referring particularly to the drawings, the motor is inclosed in the casing 6, which may be attached to the ceiling or wall in any proper manner. The power is furnished by 35 a spring 7, which drives the fan-shaft 8 by a train, which may be of any proper construction, and therefore need not be described, nothing being claimed relative thereto.

The shaft 8 is hollow and is journaled at 40 its upper end in a step-bearing 9, formed in the top plate 6^a of the casing. The shaft has a shoulder 10, which forms a bearing at a round hole in the lower plate 6^b of the casing, through which the shaft extends. At the 45 lower end of the shaft the socket-piece 11 is attached, clamped between a shoulder 12 on the shaft and a jam-nut 13, the extremity of the shaft being screw-threaded for the nut. The wings 14 of the fan are secured in the

socket-piece by set-screws 15. The wings are 50 angularly adjustable in the sockets with respect to the plane of their motion and are held at such adjustment by the set-screws. This adjustment serves, to a certain extent, to govern the speed of the fan. Extending 55 through the shaft is a long thumb-screw 16, threaded at its upper end to take into a screw-threaded hole in the top plate, and below the lower end of the shaft the screw carries a washer 17, forming a shoulder adapted to be 60 brought against the lower end of the shaft. By screwing the thumb-screw in it binds the shaft between the washer and the step-bearing, and the speed of rotation of the shaft 65 may be reduced at will or stopped, if desired.

The shank of a wing and the socket to receive it are of such shape, preferably round, that the former may be turned in the latter, so as to set the wings at the desired angle.

Having thus described the invention, what 70 we claim is—

1. In combination with a motor, a shaft driven thereby mounted in a step-bearing at one end and having fan-wings attached thereto, and means to exert endwise pressure on 75 the shaft against said bearing, to govern its speed.

2. In combination with a fixed support, a motor, a shaft driven thereby having a bearing in the support and carrying fan-wings, 80 and an adjusting-screw binding the shaft endwise to vary the speed thereof.

3. In combination, a casing, a motor, a hollow shaft having at one end a step-bearing in the casing and carrying fan-wings, a screw 85 extending through the shaft and engaging the casing at the bearing, and a washer on the screw bearing against the other end of the shaft, whereby the shaft may be bound endwise between the bearing and the washer to 90 govern its speed.

In testimony whereof we affix our signatures in presence of two witnesses.

CLARENCE R. BROCK.
WILLIAM C. BARTH.
